UNITED STATES PATENT OFFICE.

WILLIAM KELLY, OF DETROIT, MICHIGAN.

DESIGN FOR A CASING FOR MULTICYLINDER GAS-ENGINES.

41,543.

Specification for Design.

Patented July 4, 1911.

Application filed February 28, 1910. Serial No. 546,564. Term of patent 14 years.

To all whom it may concern:

Be it known that I, WILLIAM KELLY, a citizen of the United States, residing at Detroit, county of Wayne, State of Michigan, have invented a new, original, and ornamental Design for Casings for Multi-cylinder Gas-Engines, of which the following is a specification, reference being had to the accompanying drawing, which forms a part of this specification.

The figure is a perspective view of a casing for a multi-cylinder gas engine, showing my new design, the point of sight being below, to the right, and in front of the figure.

The figure shows the cylinders cast integral with the base and water jacket, and to form a symmetrical and ornamental

structure the manifolds for the exhaust and inlet are cast integral with the rest of the casing and extend laterally therefrom, toward the upper ends of the cylinders, one of said manifolds being located above the other, each having plane horizontal walls and one of said walls is common to both manifolds. The outer inclosing walls of said manifolds are substantially vertical and of the configuration shown.

I claim:—

The ornamental design for a casing for multi-cylinder gas engines, as shown and described.

WILLIAM KELLY.
